UNITED STATES PATENT OFFICE.

LEONARD S. BEALS, OF ASTORIA, NEW YORK.

DESIGN FOR BREASTPIN.

Specification forming part of Design No. 7,927, dated December 15, 1874; application filed November 28, 1874.
[Term of Patent 3½ years.]

CASE C.

To all whom it may concern:

Be it known that I, LEONARD S. BEALS, of Astoria, in the county of Queens and State of New York, have invented a Design for Breastpin and Drop, of which the following is a specification:

The nature of my design is fully represented in the accompanying drawing, to which reference is made.

The characteristic feature of this design is the imitation of the twig of a rose-bush.

In the drawing, the letter A designates my breastpin, which is formed to imitate the twig of a rose-bush. The drop B is formed similar to the pin; but in the drop the number of leaves

contained in the twig is reduced, and on the lower end of said drop a rose-flower is added.

What I claim as new, and desire to secure by Letters Patent, is—

1. The design for a breastpin, A, as shown and described.
2. The design for a breastpin, A, and drop B, as shown and described.

In testimony that I claim the foregoing I have hereunto set my hand and seal this 24th day of November, 1874.

LEONARD S. BEALS. [L. S.]
